J. P. FISHER

COMBINED PIPE CONNECTION AND ORIFICE DISK HOUSING

Filed March 8, 1921

James S. Fisher Inventor

By His Attorney
Edmund G. Borden

UNITED STATES PATENT OFFICE.

JAMES P. FISHER, OF BARTLESVILLE, OKLAHOMA, ASSIGNOR TO DOHERTY RESEARCH COMPANY, OF NEW YORK, N. Y., A CORPORATION OF DELAWARE.

COMBINED PIPE CONNECTION AND ORIFICE-DISK HOUSING.

Application filed March 3, 1921. Serial No. 450,648.

To all whom it may concern:

Be it known that I, JAMES P. FISHER, a citizen of the United States, residing at Bartlesville, in the county of Washington, State of Oklahoma, have invented certain new and useful Improvements in Combined Pipe Connections and Orifice-Disk Housings; and I do hereby declare the following to be a full, clear, and exact description of the invention, such as will enable others skilled in the art to which it appertains to make and use the same.

This invention relates to a combined pipe connection and orifice disk housing. The illustrated embodiment of the invention is of the type used in meters which measure the rate of flow of fluids in accordance with the difference in pressure on opposite sides of an orifice.

Orifice disk housings commonly comprise a pair of flanges each of which is threaded on one of the pipe sections between which the housing is interposed. In the use of the housings as formerly constructed, it has been necessary, in order to remove an orifice disk, to spread the flanges apart. The spreading of the flanges is often attended with much difficulty, and it is sometimes found that sufficient clearance to enable a disk to be withdrawn or inserted can be obtained only by bending the pipe. In such cases, the insertion or removal of an orifice disk not only requires the expenditure of much time and effort but may be the cause of weakening or even breaking the pipe.

In order to avoid these objections, an orifice disk housing of improved form has been devised, being described in Letters Patent of the United States, No. 1,273,597, granted to me on July 23, 1918.

An object of the present invention is to provide an orifice disk housing which will possess the advantages of earlier forms of housings as regards enabling the orifice disk to be securely held in place and permitting it to be easily removed for purposes of substitution or adjustment, and which will be composed of few parts which can be cheaply constructed and readily manipulated.

To this end an important feature of the invention resides in constructing the orifice disk housing of a pair of flanges spaced apart by a distance such as to permit an orifice disk to be freely inserted between them and providing means movably supported on one of the flanges for forcing the orifice disk against the other flange and for forming a fluid-tight connection between the orifice disk and the first-mentioned flange.

Other important features of the invention pertain to the form of the flanges and the construction and arrangement of the devices which form fluid-tight connections between the orifice disk and the flanges. The last-mentioned features will appear more particularly from the appended claims.

In the drawings which illustrate a preferred embodiment of the invention;

Fig. 1 is a view in side elevation of a combined pipe connection and orifice disk housing embodying the invention.

Fig. 2 is a view in elevation of the apparatus of Fig. 1, taken along the line 2—2 of Fig. 1 and

Fig. 3 is a central, vertical section of the pipe connection and orifice disk housing taken on the line 3—3 of Fig. 2.

In the illustrated construction, the adjacent ends of pipe sections 10 and 12 are threaded into flanges 14 and 16 respectively. As shown, the flange 14 is formed with a cylindrical portion 18, and the flange 16 is constructed to provide a cylindrical portion 20 of greater external diameter than the portion 18. The cylindrical portions 18 and 20 of the flanges 14 and 16 respectively extend toward each other and are spaced apart by a distance such as to permit an orifice disk 22 to be inserted between them without disturbing the relation of the flanges 14 and 16 to each other or to the pipes 10 and 12. The flanges 14 and 16 are also formed on their diametrically opposite sides with lugs 24 and 26 terminating in segment-shaped rims 28 and 30. The flanges 14 and 16 together constitute a housing for the orifice disk as well as a connection for the pipe sections 10 and 12, and when the housing

- is assembled, the contacting surfaces 32 of the rims 28 and 30 determine the relative locations of the end faces 34 and 36 of the cylindrical portions 18 and 20 of the flanges.
- 5 Bolts 31 passing through the rims 28 and 30 secure the flanges 14 and 16 together.
- The rims 28 and 30 on the lugs 24 and 26 are made relatively short so as to provide rectangular spaces 38 (Fig. 1) at each side
- 10 of the housing of sufficient length to permit an orifice disk to be readily inserted or removed through them.
- The end face 36 of the cylindrical portion 20 of the flange 16 is rabbetted on its inner 15 edge as indicated at 40 (Fig. 3) to provide clearance between the orifice disk and such portion of the face, and interposed between the outer unrabbetted portion of the face 36 and the orifice disk 22 is a gasket 42.
- 20 The gasket 42 may be relatively thin and may be readily cut without the use of special tools from a sheet of suitable material. It has been ascertained by actual use of the invention that the gasket 42 is not required
- 25 to possess any considerable degree of elasticity or compressibility so that the material of which it is composed may be comparatively inexpensive. The gasket herein illustrated is made from sheet packing of the
- 30 character known to the trade as "Permanite". For convenience in assembling the parts, the gasket 42 may be placed in proper position on the disk before it is inserted into the housing, and may be caused to adhere to
- 35 the disk by shellac or other suitable material. The gasket 42 is also preferably coated with graphite on its right hand surface where it contacts with the cylindrical portion 20 of the flange 16.
- 40 Surrounding the cylindrical portion 18 of the flange 14 is a rubber packing ring 44, which by reason of the reduced exterior diameter of the portion 18 with relation to the portion 20 of the flange 16 is of substantially
- 45 equal diameter to the gasket 42. With this construction, when an orifice disk 22 is inserted in the housing, the gasket 42 and rubber packing ring 44 engage it at directly opposite points.
- 50 A ring 46, which may conveniently be termed a pressure ring, encloses the cylindrical portion 18 at the rear of the packing ring 44. The ring 46 is turned outwardly at its rear end to form a rib 48, and abutting
- 55 against the rib 48 are a series of six screws 50 threaded into the flange 14. Surrounding the pressure ring 46 and the packing ring 44 is a third ring 52 which is herein-after sometimes referred to as a retaining
- 60 ring inasmuch as it prevents the packing ring 44 from being squeezed outwardly and retains it in close engagement with the periphery of the portion 18 of the flange 14, thereby precluding any escape of fluid between the packing ring and said portion.
- 65 From the foregoing, it will be understood that by turning the screws 50, the pressure ring 46 may be forced toward the orifice disk 22 so as to clamp the gasket 42, orifice disk 22, and rubber packing ring 44 between the pressure ring 46 and the flange 16. In this manner, a fluid-tight connection is formed between the orifice disk 22 and each of the flanges 14 and 16.
- 70 When an orifice disk is inserted in the housing, the retaining ring 52 is preferably moved into close engagement with it. In this position of the parts, the packing ring 44 is positively supported at all points so that all possibility of the ring becoming distorted is eliminated. As shown, screws 54 are provided on the flange 14 for moving the retaining ring 52 and maintaining it against the orifice disk.
- 75 In order to facilitate the formation of fluid-tight connections about the orifice disk 22, the space between the end surfaces 34 and 36 of the cylindrical portions 18 and 20 of the flanges is of such size only as will enable the orifice disk and the gasket 42 to be
- 80 readily inserted between them. The orifice disk is made quite thin, and the gasket 42 is also thin to avoid the use of unnecessary material. To the end that the packing ring 44 may have sufficient body to make it durable and to enable it to form a fluid-tight connection between the orifice disk and the flange 14, it is constructed of considerable breadth and of a thickness greater than the combined thicknesses of the orifice disk 22 and gasket 42.
- 85 In the illustrated construction the orifice disk 22 and gasket 42 have thicknesses of one-fourth and one-sixteenth inches respectively, and the packing ring 44 is made square in cross-section with a
- 90 breadth and thickness of one-half inch.
- 95 After the orifice disk housing has been assembled and installed in a pipe line, it is very desirable that the flanges 14 and 16 should not be required to be separated while
- 100 the housing continues in use. The packing ring, 44, however, deteriorates with continued use, and it is necessary from time to time to substitute a new packing ring for it.
- 105 In order that a new ring may be substituted without changing the relation of the flanges 14 and 16, the packing ring 44 is made in sections, each of which has a thickness not appreciably greater than the combined thicknesses of the orifice disk 22 and gasket 42.
- 110 As shown, the packing ring is composed of two sections, each of which has a breadth of one-half inch and a thickness of substantially one-fourth inch.
- 115 In assembling the parts of the housing, the flanges 14 and 16 are first screwed on to the pipes to be connected, after which the pressure ring 46 is placed over the cylindrical portion 18 of the flange 14, and the retaining ring 52 is slid into place over the
- 120
- 125
- 130
- 135

ring 46. The flanges 14 and 16 are then bolted together. The sections of the packing ring 44 may then be passed one at a time through the orifice disk gap and seated 5 against the pressure ring 46, which together with the ring 52 is pushed to the left (Fig. 3) away from the flange 16. The orifice disk 22 and gasket 42 are next inserted, after which the ring 52 is forced into contact 10 with the orifice plate by means of the screws 54. The assembly of the device is completed by tightening the screws 50 to compress the packing ring 44 and gasket 42 between the orifice disk and the pressure ring 15 46 and flange 16 respectively.

With the illustrated construction, the insertion, removal or adjustment of an orifice disk can be very readily accomplished, inasmuch as it requires only the tightening or 20 loosening of the screws 50 and 54. Moreover, fluid-tight connections are provided between the orifice disk and the flanges by the use of a single rubber packing ring, pressure ring, and retaining ring. It is important 25 that the number of rubber packing rings used shall be as small as possible since they are relatively expensive as compared, for example, with the gasket 42. The cost of the illustrated construction is also kept down by 30 reason of the small number of its parts.

Although the plate 22 in which the orifice is provided is referred to herein as a disk, it is manifest that the invention may be utilized in connection with orifice plates of 35 various forms.

The invention having been fully described, what is claimed as new is:

1. In a device of the class described, an orifice plate, a housing for the plate, disposed 40 between and connecting two adjacent pipe sections, said housing having a transverse opening permitting the insertion or removal of the orifice plate, a gasket interposed between the plate and the housing at one 45 side of the plate, a pressure ring surrounding a part of the housing on the other side of the plate, a packing ring between the plate and the pressure ring, a retaining ring surrounding the packing ring, means whereby 50 said retaining ring may be forced against said plate, and means connected with the housing for forcing the pressure ring toward the orifice plate so as to clamp the packing ring, orifice plate, and gasket together between the pressure ring and the housing.

2. In a device of the class described, an orifice plate, a housing for the plate arranged to connect two adjacent pipe sections, said housing comprising a pair of flanges 55 formed to present portions extending toward each other and spaced apart by a distance such as freely to permit the insertion and removal of the orifice plate between them, one of said portions being of larger external dimensions than the other, a gasket inter-

posed between the orifice plate and the portion of larger dimensions, and means associated with the portion of smaller dimensions for forcing the orifice plate against the gasket and making a fluid-tight joint between 70 the orifice plate and the flange comprising said last-mentioned portion.

3. In a device of the class described, an orifice plate, a housing for the plate arranged to connect two adjacent pipe sections, said 75 housing comprising a pair of flanges formed to present substantially cylindrical portions extending toward each other and spaced apart by a distance such as freely to permit the insertion and removal of the orifice plate between them, one of said portions being of larger size than the other, a gasket interposed between the plate and the larger cylindrical portion, a packing ring surrounding the smaller cylindrical portion opposite from the gasket, and means for forcing the packing ring against the plate.

4. In a device of the class described, an orifice plate, a housing for the plate, constructed to connect two adjacent pipe sections, the said housing comprising a pair of flanges spaced apart by a distance such as to permit the orifice plate to be inserted between them, and means for forming fluid-tight 90 joints between the plate and the housing 95 comprising a packing ring mounted on one of the flanges, a retaining ring surrounding the packing ring, and means for moving the retaining ring into close engagement with the orifice plate to provide support for the 100 packing ring adjacent to the plate.

5. In a device of the class described, an orifice plate, a housing for the plate, disposed 105 between and connecting two adjacent pipe sections, the said housing having a transverse opening permitting the insertion or removal of the orifice plate, a gasket forming a fluid-tight joint between one side of the plate and the housing, and means for forming a fluid-tight joint between the other side of the plate 110 and the housing comprising a packing ring movably mounted on the housing and of greater thickness than the combined thickness of the orifice plate and the gasket in order to impart to said ring sufficient body 115 to make it durable and to form a fluid-tight connection between the orifice plate and the housing, said ring being composed of sections, each of said sections having a thickness not appreciably greater than the combined thickness of the orifice plate and the gasket so as to enable the ring to be renewed 120 without disturbing the main assembly of the housing.

6. In a device of the class described, an orifice plate, a housing for the plate, disposed 125 between and connecting two adjacent pipe sections, the said housing having a transverse opening permitting the insertion or removal of the orifice plate, said opening be-

ing of a width sufficient only to enable the said ring being composed of sections, each plate to be readily inserted in it, and means of the said sections having a thickness less than the width of the opening so as to enable 10 for forming fluid-tight connections between the orifice plate and the housing comprising the orifice plate and the housing comprising a packing ring of greater thickness than the width of said opening in order to impart to the ring sufficient body to make it durable,

In testimony whereof I affix my signature.

JAMES P. FISHER.
